METHOD OF MANUFACTURING PENICILLIN

George H. Brown and Rudolph A. Bierwirth,
Princeton, N. J., assignors to Radio Corporation
of America, a corporation of Delaware

Application February 21, 1946, Serial No. 649,296

4 Claims. (Cl. 159—49)

1

Our present invention relates to the manufacture of the rare drug penicillin and has for its principal object to provide a simple and reliable method of manufacturing crystalline penicillin.

There are several ways of deriving the drug penicillin from its mother liquor. By way of example, the mother liquor, or a chemically abstracted concentrate thereof, may be dehydrated by the so called "freeze-drying method" (see Reichel U. S. (Reissue 20,969), or by the "electric field method" described in our now abandoned copending application Ser. No. 520,428. Alternatively, the liquor may be treated with a mixture of butyl and methyl alcohols (to prevent foaming) and dried in vacuo with the aid of a hot-plate or other conventional source of heat, as described in the application of George H. Brown, Serial No. 651,038, filed February 28, 1946.

Irrespective of the commercial or economic advantages claimed for these several ways of drying the drug it may be said that the final product in every case comprises an amorphous solid which, irrespective of its form (i. e. powder, sponge, film or tablet) is labile when stored at ordinary temperatures (i. e. temperatures higher than say, 50° F.), and hence must be kept under refrigeration.

We have now discovered that under certain conditions, later specified, it is commercially practical to produce penicillin in crystalline form and that the drug in this form may be stored for many weeks at temperatures as high as 100° F. without any appreciable loss in its potency.

As above indicated our invention is in the nature of a "discovery" and, in fact, was predicated upon our joint observation that in testing penicillin which had been dried in the "electronic centrifuge" described in Bierwirth's application Ser. No. 557,053, and now Patent No. 2,512,804, certain finished lots of the drug exhibited a much longer shelf-life and resistance to heat than other lots made by the same method from the same batch of mother liquor. We then observed the difference in the physical structure of the elemental particles of the different lots and learned that the superior product was, invariably, crystalline, and the other product amorphous. We have since ascertained, empirically, the several factors which determine the ultimate form of the drug and have formulated the following procedure for selectively achieving the crystalline and the amorphous forms thereof.

We have found that if the crystalline form is to be achieved it is essential that the mother liquor, or a relatively dilute concentration thereof,

2

be spread in a relatively thin film during the drying operation. This can be done most conveniently by subjecting an oversized receptacle containing a predetermined quantity of the liquor to centrifugal force so that it is spread in a uniformly thin film over the inner surface of the receptacle. We then subject the film of liquid to a relatively low pressure (say, one which will sustain a column of the order of 5 to 30 mm. of mercury) and to a temperature no higher than about 65° F. until its moisture content comprises less than 5 percent and preferably no more than 4 percent, by weight, of the film. The moisture content is quite critical; that is to say, if the material is removed from the drier at a time when the moisture content of the film is 5 percent or more, the resulting product will comprise an amorphous solid; whereas if its fluid content is 4 percent or less it will be crystalline in form. 10 In either event, the moisture content of the drug may be further reduced, either with radio frequency energy or in a conventional drying oven, without altering the characteristics of its elemental particles. If the mother liquor is dried, 15 ab initio, without spreading the liquid, the drug will assume the amorphous form.

Although we are not certain of the reasons for crystal formation under one set of conditions and non-crystallization under the others, we have determined that after the 4 percent (approximate) moisture-content level is reached the amount of moisture remaining in the liquor is no longer able to influence the ultimate form of the drug. We therefore believe that crystallization takes place at or about the 4 percent moisture level.

Having regard to the high degree of solubility of the active ingredient of the drug it appears that the liquor at the said 4 percent moisture-level comprises a super-saturated solution; therefore, to achieve the crystalline form it is necessary that the original dilute solution be converted into a super-saturated solution at some point during the drying cycle. In any event, we have determined that adjacent to the 4 percent moisture-level it is essential to maintain conditions which favor the very rapid production of solid nuclei, and that these conditions are present when the liquor is spread in the form of a relatively thin film so that it presents a large surface 40 of evaporation.

The figure of the drawing is a view partly in section of an apparatus that can be used in carrying out the method described.

The conditions which favor very rapid production of solid nuclei are further enhanced

when radio frequency energy is employed as the source of heat. Accordingly, in carrying our invention into effect we prefer to employ an "electronic centrifuge," such, for example, as the one shown in the accompanying drawing, wherein 1 designates an evacuable chamber containing a motor driven spindle 3 which supports a glass bottle 5 for rotation about its vertical axis between two capacitor electrodes 7 and 9 which will be understood to be energized by a suitable source 11 of high frequency current. As described by Bierwirth in his copending application Ser. No. 557,053 the source 11 may conveniently comprise a 2 kilowatt 30 megacycle oscillator.

In applying our invention to the manufacture of crystalline penicillin we prefer to start with a solution of the mother liquor in the concentration of 100,000 Oxford units per cubic centimeter. The bottle 5 would preferably have a capacity at least ten times greater than the volume of its contents so that the liquor may be spread by centrifugal force in a uniformly thin film over the inner surface thereof without spilling over. The pressure in the chamber 1 may conveniently be about 5 mm. of mercury. Under the foregoing conditions we have found that number of minutes it takes for the original solution to reach the 4 percent moisture-level is, substantially 5 times the number of cubic centimeters in the original solution. Thus, 2 cubic centimeters of a liquid, of the prescribed original concentration, will reach the 4 percent level in approximately 10 minutes. Another rapid but accurate check as to whether the product is in crystalline form is to observe whether or not the film remains on the walls of the receptacle when the spinning has stopped; if it does remain, the product is crystalline, if it flows off the said surface it is amorphous.

In the commercial practice of our invention it is preferable, in the interests of economy, to keep the liquid in the centrifuge only so long as is required to achieve the 4 percent moisture-level and to complete the drying operation in a conventional vacuum drying oven using a pressure of about 5 millimeters of mercury and a plate temperature of 65° F. or less.

What we claim is:

1. A method of making crystalline penicillin

which comprises spreading a predetermined quantity of penicillin liquor into a thin film, electrically heating said thin film in a low pressure atmosphere to a temperature no higher than 65° F. for a number of minutes substantially equal to 5 times the number of cubic centimeters in said predetermined quantity of penicillin liquor.

2. A method of making crystalline penicillin which comprises spreading a predetermined quantity of penicillin liquor into a thin film, electrically heating said thin film in a low pressure atmosphere of no more than 30 millimeters of mercury to a temperature no higher than 65° F., for a number of minutes substantially equal to five times the number of cubic centimeters in said predetermined quantity of penicillin liquor, whereby the liquid content of said film comprises substantially no more than four percent by weight, and then desiccating said film.

3. The invention as set forth in claim 1 and wherein said thin film is formed by subjecting said liquor to centrifugal force.

4. The invention as set forth in claim 1, wherein said low pressure atmosphere is of the order of five millimeters of mercury.
